UNITED STATES PATENT OFFICE.

JOSEPH V. WECKBAUGH, OF GREENWICH, CONNECTICUT.

MANUFACTURE OF PAPER CUPS.

1,359,772.

Specification of Letters Patent. Patented Nov. 23, 1920.

Application filed May 17, 1919. Serial No. 297,762.

To all whom it may concern:

Be it known that I, JOSEPH V. WECKBAUGH, a citizen of the United States, and a resident of Greenwich, in the county of 5 Fairfield and State of Connecticut, have invented certain new and useful Improvements in the Manufacture of Paper Cups, of which the following is a specification.

The invention relates to a sanitary drinking cup or container designed for temporary use, and constructed of material such as a suitable grade of paper, the cup being intended, generally, to be discarded after having been used. The construction admits, 10 also, of the cup being flattened by pressure to occupy a minimum space, and to be suitable for packing and sale.

The invention has for its object to provide a cup of this type from a suitable paper blank which is folded in an extremely simple manner to provide a liquid-tight container having a large capacity for the amount of material employed. A further object of the invention consists in providing 25 a substantially rigid mouthpiece or lip therefor and the edge of which shall not be sharp, as is the case usually with cups of the types heretofore produced. The cup, moreover, lends itself readily to manufacture in a sanitary manner. For example, it 30 may be produced from a continuous strip of material which will require no handling, the said material, also, remaining sealed or inclosed until the actual time of manufacture, 35 and the cup being capable of being manufactured and dispensed entirely by mechanical means. The invention, also, has for its object the particular method of producing such cups as well as novel mechanism for carrying out the same.

In the accompanying drawings, which illustrate the invention—

Figures 1 to 4 are diagrammatic views illustrating the different stages in the manufacture of a cup.

Fig. 5 is a perspective view of a completed cup.

Fig. 6 is a perspective view of the assembled mechanism.

Fig. 7 is a section taken on the line 7—7, Fig. 6.

Figs. 8 and 9 are sections taken, respectively, on the lines 8—8 and 9—9, Fig. 7.

Fig. 10 is a fragmentary detail in plan.

Fig. 11 is a section taken on the line 11—11, Fig. 10.

Fig. 12 is a section taken on the line 12—12, Fig. 7.

Fig. 13 is a fragmentary detail of the operating and feeding mechanism.

Fig. 14 is a fragmentary section taken on the line 14—14, Fig. 7.

Fig. 15 is a section taken on the line 15—15, Fig. 7, with portions broken away.

Similar characters of reference designate 65 corresponding parts throughout the several views.

Referring to Figs. 1 to 5, which illustrate more particularly the details of the cup and the method of manufacture thereof, 20 designates a blank of a suitable grade of paper of the required thickness and stiffness. This blank may be obtained in suitable lengths as from a continuous strip 21, being cut therefrom along the line 22 to provide a parallelogram of substantially equal sides and generally in the form of a square. One of the corners, for example, the corner 23, of the blank is turned backwardly along a line 24 perpendicular to the diagonal 25 of the parallelogram, and the blank itself is then turned over about the said diagonal 25 as an axis or folded along same, whereupon the full-length edges 26 and 27 are secured to each other in any suitable manner, for example by folding same inwardly. The edges may, also, be secured to each other by means of a suitable adhesive, or may be folded over again, or, preferably, are secured by means of a suitable binding strip 90 or metal tape 28 which is bound over same, Fig. 4. This completes the cup which is thus securely sealed approximately from bottom to top along the lengthwise edges 26 and 27, in manner indicated, providing, 95 also, a suitable mouthpiece 29. The latter is reinforced and stiffened by the backwardly turned corner 23, which serves, also, to hold the cup open as well as to round off that portion of the cup coming in contact with the mouth, thus obviating the sharp edges now found in the paper cups in general use.

It is to be noted, in this connection, that when the paper for manufacturing the cup is taken from a strip supplied in the form 100 of a roll, as hereinafter set forth, the in-

side surface is not exposed to dust and air and also is not handled during the process of manufacture, thus insuring a sanitary product.

- 5 In the manufacture of these cups in quantity and by mechanical means, the material for the blank 20 is provided by feeding forward the strip 21 of paper and simultaneously therewith a strip 28 of binding material such as metal. The latter is preferably arranged to be fed beneath the paper 21 along one edge thereof and at a slightly lesser rate than that of the strip in order to make use of the same feed rolls for both and 10 to effect a saving of metal, as hereinafter set forth. When the requisite quantity has been fed forward, both paper and metal strip are cut along the line 22 to provide the blank 20. Thereupon, or simultaneously 15 with the feeding of the material, suitable means are caused to deflect the corner 23, preferably at an angle of forty-five degrees to the direction of travel of the paper, after which the deflected portion is gripped and 20 turned under, and suitable line impressions 25 also preferably made therein along radii struck from the diagonally opposite corner. These impressions formed in the turned-over corner portion serve to assist the subsequent 30 turning operation and in the holding of the material in turned position, as well as to facilitate the final shaping of the cup, thereby adding to the appearance thereof. The entire blank is thereupon turned over about 35 the diagonal 25 as an axis or folded along said diagonal. The strip of metal 28, together with the coacting lengthwise edges 26 and 27, is then folded over and secured or bound together.
- 40 The mechanism for executing these various operations is shown assembled in Fig. 6, and wherein 40 designates a suitable framing or housing for retaining the members and mounted on a base 41, and the whole 45 may be incased in a suitable casing (not shown). The said framing is open near the bottom to allow of the completed cup being discharged therefrom. Suitable operating mechanism is provided, for example a crank 50 50 which projects from the side thereof, and is designed to be given one or more complete turns to effect the manufacture and discharge of a cup. Generally, one complete turn will serve to effect the manufacture 55 and discharge of the cup, the paper and strip to provide a blank for the next cup being fed forward by the return movement of the mechanism which is automatically accomplished as hereinafter set forth, when 60 the working turn is completed.

In the upper portion of the framing, there is removably mounted a roll 45 of the paper and adjacently thereto a roll 46 of the binding stock, both being mounted upon a suit-

able spool or core 47 common thereto and 65 carried by a spindle 48.

The paper 21 is brought downwardly from roll 45 through suitable lateral guides 50 to feed rollers 51 and 52, by which latter the paper is designed to be fed forward. 70 Simultaneously therewith, the metal stock 28, in the form of a strip perforated longitudinally along its median line, is advanced by said rollers, being guided by a suitably designed plate 53 to pass behind the paper 75 along its one edge 26. To feed this strip forward, the same passes over a reduced portion of the lower feed roller 52, Fig. 14, which, moreover, is provided with pins or teeth 54 to engage the perforations of the 80 strip, the latter being held to the periphery of the lower roller by a guide 55. Owing to the fact that the periphery of the roller for the strip portion is less than that of the portion of the roller for the paper, a lesser 85 amount of metal will be advanced relatively to the paper, as the rollers are rotated.

To effect the rotation of the said rollers 51 and 52, the shaft 56 of the upper feed roller carries at its outer end a sprocket 57 90 connected by a chain 58 with a sprocket 59 at the outer end of a cam shaft 60. To the latter is attached suitable operating means, for example the crank or handle 42. However, the feeding action occurs only after 95 one or more revolutions of the crank has been effected—that is to say, for example, on the return movement of the handle, which may be actuated automatically under the action of a return spring 61 connected 100 through cord 62 with sprocket 59 on the cam shaft. To secure this action, the shafts 56 and 60 are each provided with a ball clutch or similar device 63 and 64 to connect same to their respective sprockets, the 105 clutches being arranged to act in opposite directions, whereby only one of the two shafts is active or operable at a time, the other being idle during this period. The paper and metal are, therefore, fed only 110 after the operations of producing a cup have been completed, and are then brought into position for subsequent manufacture of a cup.

In feeding the paper forward into the 115 cup-forming mechanism hereinafter described, it is suitably guided by a lateral guide 65 along its edge 26, and its forward corner 23 is caused to abut a downwardly and backwardly directed folding member 120 66, Fig. 12, which causes the said corner portion of the paper to be deflected as shown in Fig. 1 of the drawings. Thereupon, after having been fed forward a predetermined length and deflected as shown, the paper is 125 in position for the operation of forming the cup.

Beneath the paper thus located and with

corner deflected, is pivotally mounted a turning member 70 having at the rear corner a series of pins 71 designed to hold the paper. To cause the said pins to engage the paper, an arm 72 is pivoted to the frame and carries a projection 73 directed beneath the side portion of the turning member to lift same under the action of a cam 74, rotatable with the shaft 60, as the handle is rotated in its operating direction. The arm 72 is held in this position until the operation of rotating the turning member begins, the cam 74 therefor being designed accordingly. A suitable abutment member 75, pivoted to the frame, is provided over the portion of the paper and designed to be engaged by the pins, for example being slotted for this purpose. The same is held in locked or fixed position, for a sufficient period to allow of the proper engagement, by a spring drawn arm 76 engaging a projecting pin 77 thereof, said arm together with the member 75 being designed to move out of the path of member 70 at the proper time to allow of the subsequent rotation of the said turning member.

The paper having been thus located and held to the member 70, the deflected portion 23 is completely turned under about a line 24 perpendicular to the diagonal passing through said corner portion 23, the same being accomplished through the action of the abutment 66 and a further plate 80 forming gripping members or jaws which are hinged at the forward portion of the turning member 70 and releasing as soon as the paper is folded. The inner faces of the jaws 66 and 80 are provided with suitable corrugations arranged as radii struck from the diagonally opposite corner of the paper: and as the gripping action takes place, the impressions 30 are formed thereby in the paper, the same serving to set the paper in its turned position and to facilitate the subsequent turning operation as well as giving a finished appearance to the cup.

To effect the closing of the jaw members 66 and 80, a plunger 81 is mounted for reciprocation in member 70, the same having a divided outer end to embrace the jaws and being designed to be forced outwardly under the action of an incline member 82. The latter is vertically movable in the frame and is controlled through an arm 82' of a bell crank whose other arm 83 is moved by a cam 84 on the cam shaft 60. A spring 85 insures the return of the incline member, and a spring 86 mounted within the plunger 81 returns the latter inwardly as the incline member is returned to normal position, a further spring 87 serving to open the jaw members. In order that the fold may occur substantially along the line 24, the paper at one side of the jaws is

arranged to be supported by the arm 73. At the opposite side of the line of fold 24, an arm 89 pivoted to the frame is arranged to be swung under the paper in supporting position as by means of an extension 90 of 70 the arm 72.

Immediately preceding the operation of turning, the one edge 26 of the paper is caused to be securely gripped from below between a jaw 95 hereinafter described and 75 the guide 65. A spring 96 operates to draw the jaw 95 upwardly, the said jaw being pivoted to the frame and an extension 97 thereof being released through the upward movement of an abutment or pin 98 attached to the movable knife 99 of the cutting or shearing member. The latter is composed of the said movable knife 99 and a stationary knife 100. To the movable knife 99 are secured return springs 101 to 85 return the knife to normal position, the said springs 101 being more powerful than spring 96 which tends to lift the jaw. Simultaneously with the holding of the paper, the rear end of same is cut along 90 the line 22, Fig. 1, by means of the shearing mechanism hereinbefore described, the movable knife 99 being operated from cams 102 on the cam shaft 60.

The paper blank thus provided is held 95 by the pins 71 to the turning member 70 as well as along the edge 26 between the jaw 95 and guide 65, and is then ready to be turned over, and its lengthwise edges 26 and 27 secured to each other to complete 100 the cup.

During the forward feeding of the paper and the various operations hereinbefore described, the strip of metal 28 has also been advanced as set forth, passing beneath the 105 paper and directed into guides 105 formed in the top of the sealing or securing member composed of the two pivoted jaws 95 and 106, so that the edge 26 of the paper lies thereover. Thereupon, through the 110 turning of the blank by member 70, the said edge 27 is brought over the edge 26, being turned about the blank diagonal which passes through the rearward end of the guide 65, the latter serving to hold the 115 paper along edge 26 and directing the turning to cause edge 27 to coincide substantially with edge 26. The three elements—two paper edges and metal strip—are thus in position to be securely crimped, folded 120 or bound together, as in turning one over the other. In this connection, it is to be noted that the metal strip, which has been formed with perforations equally spaced along its median line, has the edges of said 125 perforations left rough and in position to contact with the paper, thereby insuring a maximum hold thereon. To bring the edge 27 into the position noted, the turning member 70 is caused to be rotated about

- the diagonal 25 of the paper blank through the action of a rack member 110 engaging a segment 111 of the said turning member, the rack 110 being actuated through an arm 5 112 of a bell crank whose other arm 113 is controlled by a cam 114 on the cam shaft 60. The return movement is accomplished under the action of a spring 115.
- As soon as the turning action is completed, a pivoted sealing blade 120, whose motion is governed by a slotted guide 121 secured to the frame, is arranged to descend through the action of an arm 122 controlled by an eccentric or cam roller 123 on the cam 15 shaft 60. This blade is toothed along its operative edge, the teeth 124 thereof being designed to enter corresponding lateral recesses 125 in the jaws 95 and 106 to permit of the latter fully closing. As the blade 120 descends, its lower edge engages the edge 27 of the turned-over blank as well as the edge 26 thereof, holding same to the metal strip 28, whereupon the turning member 70 is returned to its home position through the 20 action of the spring 115, the said member having been released by its cam. Further downward movement of the blade results in the metal and edges 26 and 27 being forced into the V-groove of the jaw member 25 to assume a corresponding shape, the said jaws, meanwhile, being held in fixed and normal open position by an upwardly projecting abutment member 126 which engages a projection 127 of the said jaws. A cam 128 30 on the cam shaft 60 then releases this abutment member 126, and the jaws are depressed under further movement of the blade 120, closing through the action due to the pivotal mounting of the jaws, provision 35 also being made for a partial rotation thereof. The coacting jaw portions thereby compress and securely seal the edges 26 and 27, binding the metal 28 thereover substantially along its median line to complete the cup.
- 40 The toothed portion 124 has sufficient clearance to prevent the cup being held to the blade in the sealing action, and permits of the blade's withdrawal therefrom, which is accomplished through a spring 129. The 45 upward and return movement of the jaw, through the action of the spring 96, tends, moreover, to forcibly eject the cup which falls through the opening 130 provided in the lower portion of the frame.
- 50 55 I claim:
1. In a machine of the character described: feed mechanism comprising a pair of feed rollers and driving means therefor, a shaft carrying a plurality of cams, actuating means common to said cam shaft and feed rollers, interposed clutch mechanism to actuate said feed rollers in one direction of rotation only of the said actuating means, and interposed clutch mechanism to actuate

said cam shaft in the opposite direction of 65 rotation only.

2. In a machine of the character described: a paper supply roll and a metal strip supply roll, feed mechanism therefor comprising two coacting feed rollers, one of 70 which has a portion of reduced diameter provided with strip-engaging means.

3. In a machine of the character described: a paper supply roll and a metal strip supply roll, means to feed said paper 75 and metal binding strip and comprising two coacting feed rollers, one of which has a portion of reduced diameter provided with means to engage the strip, and means to hold said strip to said reduced periphery. 80

4. In a machine of the character described: a paper supply roll and a metal strip supply roll, means to displace the metal strip relatively to the paper, means to feed said paper and metal binding strip 85 and comprising two coacting feed rollers, one of which has a portion of reduced diameter provided with means to engage the strip, and means to hold said strip to said reduced periphery. 90

5. In a machine of the character described: a paper supply roll and a metal strip supply roll, means to displace the metal strip relatively to the paper, means to feed said paper and metal binding strip 95 and comprising feed rollers, one of which has a portion of reduced diameter provided with means to engage the strip, and means to guide the metal strip beneath the paper and to the reduced portion of the roller. 100

6. In mechanism of the character described: a turning member affording an abutment to deflect a corner of the advancing paper downwardly, means to fold the said corner, and means to secure the lengthwise edges of the paper to each other. 105

7. In mechanism of the character described: a turning member affording an abutment to deflect a corner of the advancing paper downwardly at an angle of ninety 110 degrees to the diagonal of the paper, means to fold the said corner, and means to secure the lengthwise edges of the paper to each other.

8. In mechanism of the character described: means to feed a strip of paper, a turning member affording an abutment to reflect a corner of the paper downwardly, means to fold the said corner and to provide impressions thereon, and means to secure the lengthwise edges of the paper to each other. 115

9. In mechanism of the character described: means to feed a strip of paper, a turning member affording an abutment to 125 deflect the forward corner of the paper downwardly, means to fold the corner, means to temporarily support the paper

- substantially at the line of fold, and means to secure the lengthwise edges of the paper to each other.
10. In apparatus of the character described; means to feed a paper strip and a metal binding strip, means to fold under a forward corner of said paper strip, a turning member for the paper, and means thereon to hold the paper thereto, means to cut the paper and metal strip, means to rotate said turning member to register the lengthwise edges of the paper blank, and means to secure the metal strip about said edges.
11. In apparatus of the character described; means to feed a paper strip and a metal binding strip, means to fold under a forward corner of said paper strip, a turning member and suitable pins projecting upwardly therefrom to engage the paper, means to cut the paper and metal strip, means to rotate said turning member to register the lengthwise edges of the paper blank, and means to secure the metal strip about said edges.
12. In apparatus of the character described; means to feed a paper strip and a metal binding strip, means to fold under a forward corner of said paper strip, a turning member and suitable pins projecting upwardly therefrom to engage the paper, means to lift said turning member to cause the pins to engage the paper, means to cut the paper and metal strip, means to rotate said turning member to register the lengthwise edges of the paper blank, and means to secure the metal strip about said edges.
13. In apparatus of the character described; means to feed a paper strip and a metal binding strip, means to fold under a forward corner of said paper strip, a turning member and suitable pins projecting upwardly therefrom to engage the paper, means to lift said turning member to cause the pins to engage the paper, means to cut the paper and metal strip, a pivoted abutment designed to receive the pins, a member positioning same and controlled by the movement of the cutting member, means to rotate said turning member to register the lengthwise edges of the paper blank, and means to secure the metal strip about said edges.
14. In apparatus of the character described; means to feed a paper strip and a metal binding strip, means to fold under a forward corner of said paper strip, a turning member for the paper and means thereon to hold the paper thereto, means to cut the paper and metal strip, means to guide the paper along one edge and means to coöperate therewith to hold the paper along said edge, means to rotate said turning member to register the lengthwise edges of the paper blank, and means to secure the metal strip about said edges.
15. In apparatus of the character described; means to feed a paper strip and a metal binding strip, means to fold under a forward corner of said paper strip, a turning member for the paper and means thereon to hold the paper thereto, means to cut the paper and metal strip, means to guide the paper along one edge, a jaw member vertically movable and adapted to hold said paper along said edge, means to rotate said turning member to register the lengthwise edges of the paper blank, and means to secure the metal strip about said edges.
16. In apparatus of the character described; means to feed a paper strip and a metal binding strip, a guide for one edge of the paper, means to fold under a forward corner of said paper strip, a turning member for the paper, and means thereon to hold the paper thereto, means to cut the paper and metal strip, a spring-drawn jaw member vertically movable to hold said paper against said guide and means controlled by the cutting means to release the jaw member, means to rotate said turning member to register the lengthwise edges of the paper blank, and means to secure the metal strip about said edges.
17. In apparatus of the character described; means to feed a paper strip and a metal binding strip, a cam shaft operating in conjunction therewith, means to fold under a forward corner of said paper strip, a turning member for the paper and means thereon to hold the paper thereto, means to cut the paper and metal strip, means to rotate said turning member and comprising a segmental gear attached thereto, a rack engaging said gear, a cam on said cam shaft to control said rack, and means to secure the metal strip about the edges of the paper.
18. In apparatus of the character described; means to feed a paper strip and a metal binding strip, means to fold under a forward corner of said paper strip, a turning member for the paper and means thereon to hold the paper thereto, means to cut the paper and metal strip, means to rotate said turning member to register the lengthwise edges of the paper blank, and means to secure the metal strip about said edges and comprising jaw members, a reciprocable blade adapted to descend between said jaw members to first form the paper and strip therein and then cause said jaws to close to secure the paper and metal together.
19. In apparatus of the character described; means to feed a paper strip and a metal binding strip, means to fold under a forward corner of said paper strip, a turning member for the paper and means thereon to hold the paper thereto, means to cut the paper and metal strip, means to rotate said turning member to register the length-

wise edges of the paper blank, and means to secure the metal strip about said edges and comprising jaws, said jaws being provided with lateral guides for the strip of metal, 5 a reciprocable blade adapted to descend between said jaws to first form the paper and strip therein and then cause said jaws to close to secure the paper and metal together.

20. In apparatus of the character described: means to feed a paper strip and a metal binding strip, means to fold under a forward corner of said paper strip, a turning member for the paper and means thereon to hold the paper thereto, means to cut 10 the paper and metal strip, means to rotate said turning member to register the lengthwise edges of the paper blank, and means to secure the metal strip about said edges and comprising jaws, a reciprocable blade adapted to descend between said jaws, said jaws being recessed to accommodate the teeth of the blade to permit closing of the jaws around the latter and the said blade first forming the paper and strip therein and 15 then causing said jaws to close to secure the paper and metal together.

21. In apparatus of the character described: means to feed a paper strip and a metal binding strip, a cam shift operating 20 in conjunction therewith, means to fold under a forward corner of said paper strip, a turning member for the paper and means thereon to hold the paper thereto, means to cut the paper and metal strip, means to rotate 25 said turning member to register the lengthwise edges of the paper blank, and means to secure the metal strip about said edges and comprising jaws, a reciprocable blade adapted to descend between said jaws to first form the paper and strip therein and 30 then cause said jaws to close to secure the paper and metal together, means to engage said blade to depress same, and a cam on said cam shaft to control said means.

45. 22. In apparatus of the character described: means to feed a paper strip and a metal binding strip, a cam shaft operating in conjunction therewith, means to fold under a forward corner of said paper strip, 50 a turning member for the paper and means thereon to hold the paper thereto, means to cut the paper and metal strip, means to rotate said turning member to register the lengthwise edges of the paper blank, and means to 55 secure the metal strip about said edges and comprising jaws, a reciprocable blade adapted to descend between said jaws to first form the paper and strip therein and then cause said jaws to close to secure the paper and metal together, means to engage 60 said blade to depress same, a cam on said cam shaft to control said means, and guiding means for said blade.

65. 23. In apparatus of the character described: means to feed a paper strip and a

metal binding strip, a cam shaft operating in conjunction therewith, means to fold under a forward corner of said paper strip, a turning member for the paper and means thereon to hold the paper thereto, means to 70 cut the paper and metal strip, means to rotate said turning member to register the lengthwise edges of the paper blank, and means to secure the metal strip about said edges and comprising jaws, a reciprocable blade adapted to descend between said jaws to first form the paper and strip therein and then cause said jaws to close to secure the paper and metal together, means to engage 75 said blade to depress same, a cam on said cam shaft to control said means, guiding means for said blade, and resilient means to return said blade.

24. In apparatus of the character described: means to feed a paper strip and a metal binding strip, means to fold under a forward corner of said paper strip, a turning member for the paper and means thereon to hold the paper thereto, means to cut the paper and metal strip, means to rotate 80 said turning member to register the lengthwise edges of the paper blank, and means to secure the metal strip about said edges, and resilient means to return the turning member.

95. 25. In apparatus of the character described: means to feed a paper strip and a metal binding strip, means to fold under a forward corner of said paper strip, a turning member for the paper and means thereon to hold the paper thereto, means to cut the paper and metal strip, means to rotate said turning member to register the lengthwise edges of the paper blank, and means to 100 secure the metal strip about said edges and comprising jaws, a reciprocable blade adapted to descend between said jaws, and abutment means to temporarily hold said jaws against descent during the downward movement of the blade.

105. 26. In apparatus of the character described: means to feed a paper strip and a metal binding strip, means to fold under a forward corner of said paper strip, a turning member for the paper and means thereon to hold the paper thereto, means to cut the paper and metal strip, means to rotate said turning member to register the lengthwise edges of the paper blank, and means to 110 secure the metal strip about said edges and comprising jaws, a reciprocable blade adapted to descend between said jaws, abutment means to temporarily hold said jaws against descent during the downward movement of the blade, and a cam to control the abutment.

115. 27. In apparatus of the character described: means to feed a paper strip and a metal binding strip, means to fold under a forward corner of said paper strip, a turning member for the paper and means there-
